CLAIM

We claim the ornamental design for a connector for transfer of fluid, as shown and described.

DESCRIPTION

FIG. 1 is a top perspective view of a connector for transfer of fluid;

FIG. 2 is a bottom perspective view of the connector for transfer of fluid;

FIG. 3 is a top view of the connector for transfer of fluid;

FIG. 4 is a bottom view of the connector for transfer of fluid;

FIG. 5 is a side view of the connector for transfer of fluid;

FIG. 6 is a front view of the connector for transfer of fluid;

FIG. 7 is a side view of the connector for transfer of fluid that opposes the side view shown in FIG. 5;

FIG. 8 is a rear view of the connector for transfer of fluid;

FIG. 9 is a perspective, cross-sectional view of the connector for transfer of fluid taken in the direction of the line shown in FIG. 7; and,

FIG. 10 is a perspective, cross-sectional view of the connector for transfer of fluid taken in the direction of the line shown in FIG. 8.
